UNITED STATES PATENT OFFICE.

LESLIE DENZEL KIMMEL, OF BLUFFTON, OHIO.

MILLED POST CONSTRUCTION FOR VARIABLE CONDENSERS.

Application filed May 26, 1923. Serial No. 641,675.

This invention aims to provide a novel means whereby the plates of a variable condenser may be assembled with the posts of the condenser.

5 It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood 10 that, within the scope of what is claimed, changes in the precise embodiment of the invention shown can be made without departing from the spirit of the invention.

In the accompanying drawings:

20 Figure 1 shows an end elevation, a device constructed in accordance with the invention; Figure 2 is a plan; Figure 3 is a section on the line 3—3 of Figure 2; Figure 4 is a fragmental section taken longitudinally 25 of one of the posts.

The parallel metal posts of a variable condenser are shown in the drawings and are marked by the numeral 1, the posts being of hexagonal cross section, if desired, and 30 being provided with transverse notches 2 which extend five-sixths of the way around the posts, that is, one of the flat outer surfaces of each post is not intersected by the notches. The notches 2 form bridges 3 in 35 the post, the outer surfaces 4 of the bridges coinciding with one of the flat longitudinal surfaces 5 of the posts. The side surfaces

of the bridges 3 converge as shown at 6, and the bridges have rounded inner ends 7. The bridges 3 extend, in a direction at right angles to their outer surfaces 4, more than half way across the post 1, as clearly shown in Figures 3 and 4. The metal plates of the condenser are marked by the numeral 8 and are of such a thickness as to fit closely 40 and frictionally in the notches 2 of the posts 1, the plates having seats or notches 9 in their edges shaped to receive the bridges 3.

The result is a strong and practical variable condenser construction in which washers and the like are dispensed with, sufficient electrical contact being accorded between the posts and the plates. 50

What is claimed is:

55 In a device of the class described, a post of hexagonal cross section provided with a transverse notch which extends five-sixths of the way around the post, one of the flat outer surfaces of the post being independent 60 of the notch, the notch forming a bridge in the post, the outer surface of the bridge coinciding with said flat surface of the post, the side surfaces of the bridge converging, and the bridge having a rounded inner end, 65 the bridge extending, in a direction at right angles to its outer surface, more than half-way across the post, and a plate received in the notch and having in its edge, a notch receiving the bridge. 70

In testimony that I claim the foregoing as my own, I have hereto affixed my signature.

LESLIE DENZEL KIMMEL.
